CLAIM

The ornamental design for: self-adjusting variable grip locking plier, as shown and described.

DESCRIPTION

FIG. 1 is a perspective view showing my new design for a self-adjusting variable grip locking plier;

FIG. 2 is a front elevational view thereof;

FIG. 3 is a rear elevational view thereof;

FIG. 4 is a top elevational view thereof;

FIG. 5 is a left side elevational view thereof, the opposite side being a mirror image thereof; and,

FIG. 6 is a bottom elevational view thereof.
